UNITED STATES PATENT OFFICE.

FRANZ EDER, OF NEW ROCHELLE, NEW YORK, ASSIGNOR TO RIVER AND RAIL TRANSPORTATION COMPANY, OF ST. LOUIS, MISSOURI, A CORPORATION OF OKLAHOMA.

MEANS FOR HOLDING CONTAINERS ON FLAT CARS.

Application filed May 24, 1921. Serial No. 472,141.

To all whom it may concern:

Be it known that I, FRANZ EDER, a citizen of the United States, and a resident of New Rochelle, county of Westchester, State of New York, have invented certain new and useful Improvements in Means for Holding Containers on Flat Cars, of which the following is a complete specification, the particular novel features being more fully pointed out in the annexed claims.

My invention is illustrated in the accompanying drawings in which Fig. 1 is a side elevation of a portion of a flat car with the containers mounted thereon.

Fig. 2 is an enlarged front view of one foot of a container.

Fig. 3 is a section therethru on the line 3—3 in Fig. 2.

Fig. 4 is a top plan view of one corner of a container,

Fig. 5 is a detail perspective view of the main corner plate,

Fig. 6 is a plan view of one end of a flat car without the containers showing the arrangement of the holding pockets,

Fig. 7 is a section thru the car on line 7—7 in Fig. 6, and

Fig. 8 is a plan view of one edge of the car showing a modified form of holding pockets.

My invention refers to the attachment of containers to flat cars, either railroad or other type of vehicles of the kind which are illustrated for instance in the U. S. patent to H. W. Kirchner, No. 1,252,810 of January 8th, 1918, on which the present invention is a particular improvement.

In the aforesaid patent the containers in which the commodity is carried are attached to the railroad cars by means of bails which are pivotally attached to the car and which are swung over lugs fastened on the containers. This mode of fastening has the disadvantage that it becomes necessary for the loading crew to individually fasten the containers by operating the one or several bails on each side of the container, and furthermore it has the disadvantage that by such arrangement of the fastenings the flat car becomes useless for transporting other freight such as for iron girders or beams, on account of the fastening devices being then in the way.

My improved holding means has the prin-

cipal object of leaving the entire car platform clear to be used in any ordinary manner as heretofore if it is not desired to carry unit containers as for instance shown and described in the aforesaid patent. Moreover a further advantage of my improvement is that the loading crew may place the containers on the car without further attention to individually fastening them, because if properly placed my improved means will hold the containers on the car against shifting or tilting either longitudinally or laterally.

Referring to Fig. 1 of the drawings, 1 represents a flat railroad car of the conventional type on which individual freight containers 2 such as are referred to in the aforesaid patent are placed. As will be seen from Fig. 7 the containers extend entirely across the car, straddling the same with their feet 3.

In order to secure the containers against tilting, especially longitudinally of the car, in case the latter is exposed to heavy impacts, I provide on the outer longitudinal edges of the car a series of pockets 4, (see for instance Fig. 6), one pocket for each container foot. The feet 3 are of sufficient length and the pockets are of sufficient depth to prevent the container from tilting out of the pockets in case of heavy impacts as mentioned before.

These pockets 4 are arranged in such manner that they will not interfere with the conventional stake pockets 5 usually provided on flat railroad cars. One form of the construction of these pockets 4 is shown in Fig. 6, where each pocket is formed at its two ends by channel-irons 6 riveted to the outer edge of the car, the channel-irons 6 of all the pockets on one side being joined by a piece of flat iron 7 which is riveted thereto. Pockets 4 are of sufficient height transversely of the car so as to clear the stake pockets 5 which are nested in between the container pockets as shown in Fig. 6. By this construction a very rigid form of pocket is obtained in which the pockets support each other, so that the twisting of the pockets is avoided in case the container should be accidentally tilted by an impact longitudinally of the car.

The freight containers 2 which are preferably constructed of sheet iron, are provided

preferably with feet 3 also constructed of sheet metal in order to reduce the weight of the feet to the smallest possible amount without impairing their resistance against the twisting strains to which they are exposed during transportation.

A convenient form of container feet is shown in Figs. 2 to 5. As is shown in cross section in Fig. 3 each foot consists of two corner plates 8 and 9, which are shown in perspective view in Fig. 5. Between the vertical sides of these plates are disposed distance pieces 10 of solid casting, the form of which is shown in dot-dash lines in Fig. 5. The two plates are held together by rivets 11 which clamp the distance pieces 10 tightly between the plates. The central portions of plates 8 and 9 are also held together by rivets 12, spacing ferrules 13 being interposed between the plates as shown in Fig. 3. The outer corner plate 9 extends a sufficient distance upwards as shown at 9^a in Figs. 1, 2 and 5, so as to form a good brace for the container corners.

A modified form in which the foot pockets for the containers may be constructed is shown in Fig. 8. In this case each pocket consists of a U-shaped member 14 with outwardly flanged edges 15 which are secured to the side of the car. In order to render the pockets 14 rigid and in order to mutually support the pockets as in the modification shown in Fig. 6, channel shaped distance pieces 16 are interposed between adjacent pockets and suitably attached thereto (not shown). In the spaces between pockets 14 and covered by distance pieces 16 the conventional stake pockets 5 may be conven-

iently placed, so that the flat car becomes available for all the other uses of which ordinary flat cars are capable.

While I have shown and described particularly preferred forms of container feet and foot pockets, I do not wish to limit myself to these particular forms, because the novel idea involved in my invention is not limited to these detail constructions.

What I claim is:

1. In a carrier of the character described, a platform, containers disposed thereon and extending across the full width thereof and having feet with which the containers straddle said platform and means provided at the outer edges of said platform for receiving said feet to prevent the containers from shifting and tilting on said platform.

2. In a carrier of the character described, a platform, containers disposed thereon and extending across the full width thereof and having feet with which the containers straddle said platform and pockets provided at the outer edges of said platform for receiving said feet and having sufficient depth to prevent the containers from shifting and tilting on said platform.

3. In a carrier of the character described, a platform, containers disposed thereon and extending across the full width thereof and having feet with which the containers straddle said platform and pockets provided at the outer edges of said platform for receiving said feet and having sufficient depth to prevent the containers from shifting and tilting on said platform, said pockets being mutually supported against each other.

FRANZ EDER.
